(57) **CLAIM**

The ornamental design for a bison, as shown and described.

DESCRIPTION

FIG. 1 is a top axonometric view of a bison showing the new design;

FIG. 2 is a bottom axonometric view of the bison;

FIG. 3 is a top elevation view of the bison;

FIG. 4 is a bottom elevation view of the bison;

FIG. 5 is a front elevation view of the bison;

FIG. 6 is a left elevation view of the bison;

FIG. 7 is a right elevation view of the bison;

FIG. 8 is a rear elevation view of the bison;

FIG. 9 is a right elevation view of the bison with a backward-extending front left leg, a frontward-extending front right leg, a front-extending rear left leg, and a backward-extending rear right leg;

FIG. 10 is a left elevation view of the bison with a forward-extending front left leg, a backward-extending front right leg, a front-extending rear right leg, and a backward-extending rear left leg;

FIG. 11 is a right elevation view of the bison with a backward-extending front right leg, a frontward-extending front left leg, a front-extending rear right leg, and a backward-extending rear left leg;

FIG. 12 is a left elevation view of the bison with a forward-extending front right leg, a backward-extending front left leg, a front-extending rear left leg, and a backward-extending rear right leg;

FIG. 13 is top perspective view of the bison; and,

FIG. 14 is a bottom perspective view of the bison.

1 Claim, 14 Drawing Sheets
